Primary Examiner — Kevin K Rudzinski*Assistant Examiner* — Amber J Rabie(57) CLAIM

The ornamental design for a bag for skis as shown and described.

DESCRIPTION

1. Bag for skis
- 1.1 : Perspective
- 1.2 : Front
- 1.3 : Back
- 1.4 : Top
- 1.5 : Bottom
- 1.6 : Left
- 1.7 : Right

The characteristic features of the design lie in the shape of the "bag for skis"; the materials of the design are fabric, metal, or synthetic resin; the design is a bag for skis that safely stores skis and boards; it can be adjusted by folding the top depending on the size of the items being stored, and it is equipped with wheels at the bottom for light and convenient movement.
